UNITED STATES PATENT OFFICE.

WILLIAM E. NICKERSON, OF CAMBRIDGE, MASSACHUSETTS, ASSIGNOR TO GILLETTE SAFETY RAZOR COMPANY, OF BOSTON, MASSACHUSETTS, A CORPORATION OF MAINE

MACHINE FOR PRINTING AND FOR OTHER PURPOSES.

1,075,989.

Specification of Letters Patent. Patented Oct. 14, 1913.

Application filed February 16, 1906. Serial No. 301,482.

To all whom it may concern:

Be it known that I, WILLIAM E. NICKERSON, of the city of Cambridge, county of Middlesex, and State of Massachusetts, have invented certain new and useful Improvements in Machines for Printing and for other Purposes, of which the following is a specification.

The improvement relates to machines designed to print, etch or stamp upon small flat articles and is especially adapted for printing on both sides of a razor blade of the Gillette type, but may readily be adapted to and used for printing, etching, stamping or marking other articles.

The principal objects of the invention are to provide means for automatically picking up, and transferring razor blades or other articles from a pile or stack to a printing block, and to provide means for transferring such blades after being printed on one side, to a second printing block where they are printed on the other side and finally thrown off or delivered from the machine to a receptacle or as desired.

The invention consists in the combinations of devices, parts, and means for producing the effects intended, as hereinafter more fully described and pointed out or indicated in and by the claims.

As the make up of the machine is such as to readily lend itself to a division of the coöperating parts into groups, most of which go back to the main shaft for their impulse, it will be convenient to designate each of these groups by a letter and their members or related parts by the same letter with an appropriate cardinal index number. It may, however, be premised that the several groups comprise the frame work and fixed supporting parts; the main shaft and power supply parts; the supply or stack plate and related parts; the carrying arm and its connections; the suction cylinder and operating connections; the first printing block and connections; the first printing arm and connecting or related parts; the first inking pad and connections; the second printing block and connections; the second printing arm; the second inking pad, the throw off arm and its connection, and the group for automatically shutting off the power when a stack of blades has been exhausted.

In the drawings Figure 1 is a front elevation of the machine, Fig. 2 a side eleva-

tion thereof, and Fig. 3 a plan view. Fig. 4 is an enlarged vertical section of the upper part of the machine taken on the line 4, 4, of Fig. 1, looking in the direction indicated by the arrow. Fig. 5 is an enlarged horizontal section looking down on parts of the machine from the line 5, 5, of Fig. 1, on which this view is taken. Fig. 6 is an enlarged plan view of the printing blocks when in printing position along with their pivoted carrying arms and the throw-off arm. Fig. 7 is a vertical section taken on the line 7, 7, of Fig. 6, with dotted lines showing the positions of the two printing blocks and their carrying arms with a razor blade in transit, the point reached being 135° from the start of the semi-circle. Fig. 8 is an enlarged plan view of one of the inking pads on which the first printing or type arm is resting, and shows the mechanism for gradually rotating the inking pad and for keeping the stripper pin from touching it. Fig. 9 is an elevation, partly in section, taken on the line 9, 9, of Fig. 8, and Fig. 10 is a sectional detail taken on the line 10, 10, of Fig. 8, showing an eccentric lock roller and part of the ink-pad dish. Fig. 11 is an enlarged sectional detail of the printing arm and type block resting upon a razor blade, as in the act of printing, the stripper pin being also shown as resting upon the blade supported on the printing block. Fig. 12 is a similar view of the same parts and shows the printing arm moved upward somewhat from the blade, while the stripper pin still rests on the blade, which it has detached from the type block. Fig. 13 is an enlarged plan of the stack plate for carrying a supply of the blades to be printed, and also shows the automatic latch for governing the movements of the stack plate, the pivot pin of the latch being at its extreme throw toward the back. Fig. 14 is an elevation of the parts shown in Fig. 13 with the addition of the mechanism by which the stack plate latch is operated. Fig. 15 is an elevation of the stack plate and latch, the latter being in the releasing position. Fig. 16 is an enlarged detail partly in section of the suction carrying arm and of part of the stack plate, the arm being shown in the act of taking up the last blade from the stack plate. Fig. 17 is also an enlarged detail of the suction carrying arm partly in side elevation and partly in

a section taken on the line 17, 17, of Fig. 16, the support being shown broken. Fig. 17 also shows part of the mechanism for stopping the operation of the device when the 5 last blade has been removed from the stack plate, or when one of the stacks has been exhausted. Fig. 18 is an enlarged detail of a latch for automatically stopping the operation of the suction lifting arm. Fig. 19 is 10 an enlarged view partly in vertical section of a suction cylinder and piston which operate in connection with the suction blade carrying arm. This figure shows the cam which raises the piston, and the piston sufficiently raised to partly uncover the inlet port. Fig. 20 is a plan of the piston shown in Fig. 19, with related parts removed and the ports exposed to view. Fig. 21 is an enlarged plan of a retaining plate for the piston 20 ton rod and also shows ports. Fig. 22 shows a razor blade with printing thereon as done by the first printing arm and printing block, and Fig. 23 shows recesses in the second printing block corresponding with the 25 printing done by the first printing block so as to prevent blurring when the blade with a fresh imprint is transferred from the first to the second printing block. Fig. 24 is a vertical section of the second printing block 30 taken on the line 24, 24, of Fig. 23, showing the depth of the recesses for preventing blurring. Fig. 25 is a bottom plan of the suction pad. The remaining figures are dia- 35 grammatic views, in sequence, of different positions of a suction carrying arm, throw off and printing arms, printing blocks and their arms. The carrying arm in Fig. 26 is raised and about to swing over the first printing block, while both printing arms are 40 at rest on their inking pads. The only changes in position of the parts which Fig. 27 shows, are in the suction carrying arm which is placing a blade on the first printing block, and in the stack plate which is in the 45 act of making a quarter rotation. The changes shown by Fig. 28 are: The stack plate has completed its quarter rotation, the suction carrying arm is over the stack plate and a blade is being printed by the first 50 printing arm on the first printing block. In Fig. 29 the second printing block has folded over on to the first printing block preparatory to a transfer of the blade, the first printing arm has returned to its inking pad 55 and the suction carrying arm has dropped upon a blade stack and is ready to raise a blade from the stack brought into position by the quarter rotation of the stack plate. The only change shown by Fig. 30 is that 60 both printing arms have turned over together on their common pivot so that the first block is uppermost and the blade is resting on the second block. In Fig. 31 the first printing block has returned to its 65 printing position after leaving the blade on

the second block where it is being printed by the second printing arm. Fig. 32 completes the cycle of movements. The second printing arm has returned to its inking pad, the throw-off arm is tossing the blade into some receptacle and is about to return to its first position. The only difference in the cycle of movements shown by these diagrams from the actual operation is that in practice the suction carrying arm and the 70 first printing arm do not wait for the throw-off arm to work and complete a cycle, but begin a new cycle as soon as the later movements are far enough advanced to avoid interference. 75

In the drawings, A (Figs. 1, 2 and 3) is the general base plate resting upon the floor, and A¹ (Figs. 1, 2, 3, 4 and 5), the supporting framework adapted, in combination with the top or table A² (Figs. 1, 2, 3, 4, 6, 7, 8, 9, 10, 11, 12, 13 and 19) to carry the various working members of the device and their related parts. 80

The general power shaft B (Figs. 1, 2, 4, 5, and 14), operates the various groups of members by means of cams, excepting the stack plate which is driven by a belt and pulleys, (Fig. 1) so that one rotation of the shaft produces a complete cycle of movements. The shaft B is journaled in the framework A¹ at B¹ and B² (Figs. 1 and 5) and is itself driven continuously 90 through the gear B³ (Figs. 1 and 5) by the pinion B⁴ (Fig. 1) which is mounted upon the auxiliary driving shaft B⁵ (Figs. 1, 3, 4 and 5) itself also journaled in the framework A¹ as shown at B⁶ and B⁷ (Fig. 1) and carrying upon one end the tight pulley B⁸ and loose pulley B⁹ (Figs. 1, 3 and 5) by means of which it is driven in the usual 95 manner. 100

The supply of blades to be printed is arranged in piles or stacks on the stack plate C (Figs. 1, 2, 3, 4, 13, 14, 15, 16, 17, and 26 to 32 inclusive). The blades have holes in them as shown in Fig. 22, and are held in position by the vertical pins C¹, C², as shown in Fig. 3. Resting upon the stack plate underneath each stack of blades is a block C² of substantially the same plan view as 115 a blade, excepting that the central part is cut out forming a recess under the bottom blade of each stack. These blocks C², C² are shown plainly in Figs. 4, 16 and 17. They coöperate with automatic stopping 120 mechanism as will hereafter appear.

The stack plate C is mounted rigidly on the upper end of the vertical spindle C³ which is journaled at C⁴ and C⁵ in the U shaped bracket C⁶, the latter being bolted 125 to the edge of the table A² (see Figs. 1, 2, 3, 4, 13, 14 and 15). The spindle C³ is vertically supported by a friction disk C⁷ which rests in turn upon the upper side of the pulley C⁸ (Figs. 1, 2, 4, 14 and 15). There is 130

preferably a leather washer C⁹ between the disk C⁷ and the pulley C⁸ as shown in Figs. 14 and 15. The disk C⁷ is rigidly, and the pulley C⁸ loosely mounted on the spindle C³. Continuous rotation is imparted to the pulley C⁸ by the belt C¹⁰ which runs over the idler pulleys C¹¹ and C¹² (Figs. 1, 2 and 3) to the pulley C¹³ mounted on the main power shaft B (Figs. 1 and 5). This gives the stack plate C a constant tendency to rotate, but it is restrained from so doing by the stack plate latch C¹⁴ which is pivoted at C¹⁵ and engages by means of the shoulder C¹⁶ with the latch pieces C¹⁷, C¹⁸, on the stack plate C (Figs. 3, 13, 14 and 15).

At each cycle of movements it is desirable that the stack plate rotate a quarter turn and bring another stack of blades into position, in order that all the stacks be acted upon. This is accomplished at the proper part of each cycle by the momentary disengagement of the stack plate latch C¹⁴, by means of the cam C¹⁹ (Figs. 1, 5 and 14) mounted on the main power shaft B, said cam acting through the roller C²⁰ and the lever C²¹ (Fig. 14) the latter being pivoted at C²¹ and having pivoted to it, at the upper end, the pull rod C²² which engages by means of a shoulder C²³ with a dependent portion C²⁴ of the said stack plate latch. The pull rod C²² rests upon a horizontal ledge C²⁵ on the dependent portion C²⁴ of the latch C¹⁴, and is kept from being laterally displaced by a guard piece C²⁶. When the pull rod C²² is drawn back by the connected lever and its cam, the pull rod shoulder C²³, after having moved the latch, is pried out of engagement by the lifting of said rod C²² by the rear end of the ledge C²⁵ as the latter assumes an inclined position as shown in Fig. 15, and the latch C¹⁴, which has been momentarily disengaged from the stack plate latch piece C¹⁷, is allowed to be drawn back into the engagement position by the latch spring C²⁷. This latch mechanism is best seen in Figs. 13, 14 and 15.

The next group of members in order consists of the suction carrying arm D (Figs. 1, 2, 3, 4, 5, 16 and 17) and its immediately related parts. The construction of the arm itself is best seen in detail in Figs. 16 and 17. The suction arm D is rigidly mounted, by means of the hub D¹ and the set screw D², on the upper end of the vertical rod D³ which is arranged to have a reciprocating vertical motion and also a motion of partial rotation, as will be hereinafter described. The rod D³ is guided by the boxes D⁴ and D⁵, the former located in the table A², and the latter at the outer end of the rigid arm D⁶ which is bolted to the main framework A¹ at D⁷. The suction carrying arm D (Figs. 16 and 17) is provided with an extension piece D⁸ projecting laterally

from the hub D¹ at a right angle to the arm itself, and having the stop screws D⁹ and D¹⁰ provided with lock nuts as shown. These stop screws serve, in connection, respectively, with the standards D¹¹ and D¹² mounted rigidly in the table A², to limit and adjust the lateral swing of the arm D when it is moved by the vertical rod D³ (Figs. 1 and 3). Vertical reciprocal movement is given to the rod D³ by the lever D¹³ which is forked at its outer end and provided with rollers D¹⁴ (Figs. 1 and 5), these rollers supporting the rod by means of the collar D¹⁵ rigidly attached to it. The lever D¹³ is pivoted at D¹⁶ to the bracket D¹⁷ which is rigidly secured at D¹⁸ to the table A². The lever D¹³ is operated by the cam D¹⁹, the lever being provided with the roller D²⁰ which bears on the top of the cam, the latter being mounted on the main power shaft B. This is best seen by the dotted lines in Fig. 4. The rod D³ is given partial rotation in one direction by means of an extensible and elastic pull rod D²¹ connected at one end to an arm D²² rigidly secured to said rod D³ and at its other end to the arm C²⁰ which is operated by the cam C¹⁹ as previously described. In opposition to the foregoing, the rod D³ is reversely rotated by the weight D²³ acting on the arm D²⁴, through the cord D²⁵ which passes over the idler pulley D²⁶, the said arm D²⁴ being rigidly mounted on the rod D³.

The combined movements of the rod D³, derived from the above described mechanisms, are such as to cause the attached suction carrying arm to rise from a blade stack, then swing over the first printing block (to be hereinafter described), to drop upon the said block, then to rise again and after swinging back over the blade stack, to drop again thereon, thus completing its cycle.

The suction carrying arm D is provided at its outer end with a suction pad D²⁷ (Fig. 25), preferably of rubber and consisting of a flat top part D²⁸ having a downwardly projecting ring-like part D²⁹ with a central piece D³⁰, producing together an annular suction space D³¹ which is applied to the surface of a blade, the central piece D³⁰ closing the central hole in the blade. The suction pad D²⁷ has a small perforation D³² which registers with a similar perforation D³³ in the block D³⁴, preferably of wood, to which the rubber pad is cemented. The perforation D³³ registers again with a passageway D³⁵ in the arm D, to which the block D³⁴ is fastened by means of the clamps D³⁶ having the binding screws D³⁷ as shown (Fig. 17). The passage D³⁵ connects with another passage D³⁸ in the arm D which connects in turn by means of the nipple D³⁹ with the flexible tube D⁴⁰, the latter leading to a suction cylinder which will be described separately.

The suction for lifting and carrying the blades by the arm D is produced by the cylinder E and piston E¹ (Figs. 1, 2, 3, 5, 19, 20 and 21), the principal view being in Fig. 19. The cylinder E is firmly fastened to the main framework A¹ and is closed at the bottom by the head E² projecting inwardly as shown. The upper end is provided with the head E³ having provision for the passage of the piston rod E⁴, which has an enlarged part E⁵ at its lower end and is thereby held to the piston E¹ by the plate E⁶ having the recess E⁷, the said plate E⁶ being fastened to the piston by the screws E⁸, E⁹ as shown. The ports E⁹, E¹⁰ through the piston E¹ and plate E⁶ are closed to downward passage by the upwardly opening valve E¹⁰ which slides on the piston rod E⁴ and is pressed upon the weight E¹¹ which also slides upon the said piston rod. The inlet port E¹² is a little above the bottom of the cylinder so that it is not uncovered until the piston has moved upward somewhat, whereby a high vacuum is first formed under the rising piston, so that when the port is uncovered by the further rise of the piston a sharp suction is produced in the arm D adapted to draw the blade firmly against the rubber suction pad D²⁷.

Ingress and egress of air in the cylinder E above the piston is provided for by the port E¹³, the receptacle E¹⁴ with the shield E¹⁵ being useful for preventing the blowing out of spray from the oil which is used to seal and lubricate the piston. The piston rod E⁴ is also enlarged at the upper end E¹⁶ and is thereby loosely, but strongly, attached to the lifting rod E¹⁷ by the collar E¹⁸ which is held upon the lifting rod by the transverse pin E¹⁹. The lifting rod E¹⁷ slides vertically through the guide boxes E²⁰ and E²¹, each of which is bolted to the main framework A¹ as shown in Fig. 1, and is provided with a roller E²² mounted upon a pin inserted in the lifting rod, and the roller bears upon the cam E²³ which is mounted on the main power shaft B at its end. The cam E²³ is of such a shape that the piston E¹ is gradually lifted while a blade is being raised and carried to the printing block and then drops quickly as the blade is placed upon the block in order that the blade may be released or blown off the carrying arm onto the block without loss of time. Rotation of the lifting rod E¹⁷ is prevented by extending the pin E²⁴ upon which the roller E²² is mounted, so as to take another roller E²⁵, which travels between the vertical parallel bars E²⁶ which are fastened at their upper and lower ends, to the guide box bases as shown (Figs. 1 and 2). The inlet port E¹² is connected with the flexible tube D²⁶, of the suction lifting arm group, by the pipe system E²⁷, E²⁸.

The first printing block F (Figs. 6, 7, 11 and 12) is provided with a supporting arm F¹ (Figs. 3, 6 and 7) pivoted upon the horizontal pin F², the latter being housed at the ends, in two lugs F³, F⁴, projecting upward from the table A². By means of this pivot the first printing block F can be folded over onto the second printing block, as will be shown later on. Movement in one direction is given to the block F and its arm F¹ by the cam F⁴ mounted on the main power shaft B (Figs. 1 and 5) acting upon the roller F⁵, arm F⁶ pivoted at F⁷ (Figs. 4 and 5), said arm being connected at its upper end by the cord F⁸, which passes over the idler pulley F⁹, with the segment pulley F¹⁰, the latter being integral with the arm F¹. Movement in the opposite direction is imparted to the arm F¹ and block F by the weight F¹¹ acting through the cord F¹² and segment pulley F¹³, the latter being also integral with the arm F¹. The cam serves to fold the first printing block F and its arm over onto the second printing block for transferring the blade from the first to the second block and the weight swings it back when the cam and lever return. The printing block F rests normally on the adjusting screw F¹⁴ located in the table A², whereby the height of the block is exactly regulated (Figs. 7, 11 and 12). The block F is provided with two upwardly projecting pins F¹⁵, F¹⁶, which keep the blade in the proper position while being printed and also during its transfer to the second printing block. The pins F¹⁵, F¹⁶ are somewhat tapered or rounded at the outer ends, but have a small conical depression at the extreme ends, the use of which will be explained later. After a blade is dropped over the pins F¹⁵, F¹⁶ on the printing block F by the suction carrying arm D the printing of the first side of the blade is performed by the first printing arm G (Figs. 3, 4, 8, 9, 11 and 12). The arm G is rigidly mounted on the vertical rod G¹ (Figs. 1, 3, 4, 5, 8 and 9) which is movably mounted in the supports G² and G³, the former in the table A² and the latter secured to the framework A¹. The rod G¹ is vertically supported by the arm G⁴, the latter being rotatably mounted on the rod and having above it the collar G⁵ rigidly secured to said rod (Fig. 4). The arm G⁴ is provided with a roller G⁶ (seen in dotted lines in Figs. 4 and 5) which rests upon the cam G⁷ mounted upon the main power shaft B (Fig. 5 and dotted lines in Figs. 3 and 4). The cam G⁷ lifts the arm G⁴ and with it the rod G¹ and printing arm G, twice at each rotation of the shaft B, or in one cycle, once off the inking pad and once off the printing block. The rod G¹ is given a partial rotation and the printing arm thereby swung back and forth between the inking pad and the printing block by means of the (130)

wing-like arm G^2 rigidly mounted on the rod G^1 , and acted upon horizontally by the cam G^9 (Figs. 1, 3, 4 and 5) the latter being mounted on the main power shaft B, and the helical spring G^{10} (Fig. 1) attached to the framework A^1 at one end and at the other to the arm G^{11} (Fig. 4), the latter being integral with the collar G^6 before described, said spring rotating the rod in opposition to the cam. At the outer end of the printing arm G is attached the type block G^{12} (Figs. 1, 4, 9, 11 and 12). It is removably secured to the arm G by the clamp piece G^{13} , having the spring G^{14} (Figs. 9, 11 and 12). The lower ends of the clamp piece are turned inward at a right angle and engage with ledges on the sides of the type block, while the spring keeps tension on the clamp piece to hold the type block firmly. There are four adjusting screws G^{15} , G^{16} in the arm G against which the clamp piece presses the type block and which are used for leveling the latter (Figs. 8, 9, 11 and 12). The type block G^{12} is kept horizontally in the proper position by the locating pins G^{16} , G^{18} , and is provided with recesses G^{17} , G^{18} , on its under side to accommodate the pins F^{15} , F^{16} of the printing block F (Figs. 11 and 12).

The arm G is further provided with a stripper pin G^{18} which serves to detach the blade from the type to which it tends to adhere when the printing arm rises from the printing block. The stripper pin G^{18} traverses a vertical passage passing through the clamp piece G^{13} , arm G, and type block G^{12} , as shown in Figs. 9, 11 and 12. Fig. 11 shows the type block, having the type face G^{19} , and the stripper pin G^{18} resting on a blade which is supported on the printing block F. Fig. 12 shows the type block slightly raised and the stripper pin still on the blade which it has detached from the type. In order to prevent the stripper pin G^{18} from touching the inking pad when the type presses upon it, the pin is provided with a bar G^{20} the forked end of which engages with a groove in the upper part of the pin, the other end of the bar being loosely pivoted on the stud G^{21} secured to the arm G. When the type is dropped onto the inking pad the extreme outer end of the bar G^{20} engages with a stop bar G^{22} , the latter being supported by the post G^{23} which is rigidly attached to the table A^2 . This serves to prevent the stripper pin from descending low enough to touch the ink pad and thus avoids soiling the blade where the stripper pin comes in contact with it (see Figs. 8 and 9). The position horizontally of the arm G when over the printing block F is exactly defined by the adjustable stop screw G^{24} which, in this position of the arm, engages with the rigid limiting post G^{25} (Figs. 3 and 4), projecting vertically from

the table A^2 , the spring G^{10} throwing the arm against the limiting post and the cam G^9 swinging it over the inking pad.

It is desirable that the pressure of the type shall be adjustable both on the blade and on the inking pad. Therefore the vertical rod G^1 , which carries and operates the printing arm G, is provided with the removable weights G^{26} which are supported on the rod by a collar underneath them as shown in Figs. 1, 4 and 5. The weights have a radial slot G^{27} somewhat narrower than the diameter of the rod, the latter being flattened on two sides at G^{28} above the weights, so that they may be easily added or removed (Figs. 1, 4 and 5). As it is usually advisable to use less pressure on the inking pad than on the blade, the rod G^1 is also provided with a short horizontal arm G^{29} rigidly mounted upon it (Figs. 1, 4 and 5). This arm G^{29} is so positioned upon the rod that when the latter descends with the printing arm G over the printing block F, the said arm G^{29} has a clear path, but when the rod descends to apply the type to the inking pad H, the said arm engages with the lever G^{30} , pivoted at G^{31} , and carrying beyond the pivot the weight G^{32} , and thereby encounters the resistance due to raising said weight, which resistance proportionately lessens the pressure of the type on the inking pad (Figs. 1, 4 and 5). The weight G^{32} , being movable on the lever G^{30} , the said pressure can be regulated at will.

Ink for the type on the arm G is supplied by the inking pad H, which consists of any suitable bibulous material like blotting paper, which is supported by the flat-bottomed dish H^1 , the latter being rotatably mounted by means of the hub H^2 on the vertical pin H^3 fixed in the table A^2 (Figs. 3, 4, 8 and 9). The dish H^1 rests upon the disk-like end of the mover arm H^4 , which is pivoted upon the pin H^3 , as shown in dotted lines in Figs. 8 and partially in section in Fig. 9, the friction washer H^5 being inserted between the arm and the hub of the disk as shown in Fig. 9. The outer end of the arm H^4 is connected by the loosely pivoted bar H^6 with the short horizontal arm H^7 rigidly mounted on the rod G^1 , the partial rotations of the latter serving to move the arm H^4 back and forth about its pivot on the pin H^3 . This tends to give the dish H^1 a partial rotation in each direction. The dish, however, is restrained from rotating in one direction by the eccentric lock roller H (Figs. 8 and 10) which is rotatably mounted on the fixed pin H^3 and engages with the edge of the dish H^1 , thereby allowing the dish to rotate by degrees in one direction only, for the purpose of bringing different parts of the inking pad under

the type. The eccentric lock roller H^8 is provided with a spring H^{10} (Figs. 8 and 10) by means of which it tends to turn in the direction of the arrow, and so as to lock the dish against any backward movement.

5 Mounted upon the same pivot pin F^2 as the first printing block F , is the second printing block I , the latter being provided with the forked supporting arm I^1 which has integral with it at each end the segment pulleys I^2 and I^3 , respectively (Figs. 1, 3, 6 and 7). The block I is made to swing around the pivot pin F^2 and fold over onto the first printing block F by means of the 10 cam I^4 (Fig. 5), lever I^5 (Figs. 1 and 5), cord I^6 , idler pulley I^7 and segment pulley I^8 , and is returned to the printing position by the weight I^9 (Fig. 4), acting through the cord I^9 on the segment pulley I^2 , in substantially the same way as the first printing 15 block F is operated by its connected mechanism. The face of the second printing block I , unlike that of the first printing block F , has recesses I^{10} , which register with the first printed impression when the blade is turned over onto it, and so avoids contact with the fresh ink, and consequent blurring. These recesses are well shown in Figs. 6 and 20 23, and Fig. 22 shows the printing of the first side of the blade where the lettering 25 agrees in position with the recesses. Fig. 24 shows the depth of the recesses. The second printing block I , like the first printing block, has an adjustable support in the screw 30 I^{11} (Fig. 7), and is provided with two sharp pointed locating pins I^{12} , I^{13} (Figs. 6 and 7).

The blade, after being transferred to the second printing block I , having been printed 35 on one side by the first printing arm G , is printed on the remaining side by the second printing arm J . This second printing arm is provided with a type block and accessories, including inking mechanisms, in all 40 respects similar to those appertaining to the first printing arm G , excepting that those governing the horizontal movements and the inking mechanisms are opposite handed. The type block for the second arm J takes 45 ink from an inking pad K , and the arm J operates in exactly the same manner as the first printing arm G . The accessory mechanisms of the arm J wherever designated by letters in the drawings, carry the letter J 50 with the same cardinal index number as is carried by the corresponding accessory parts of the first printing arm G . The corresponding parts are, vertical rod J^1 , supports J^2 and J^3 , arm J^4 , collar J^5 , roller J^6 , cam J^7 , wing-like arm J^8 , cam J^9 , helical spring J^{10} , arm J^{11} , type block J^{12} , clamp piece J^{13} , adjusting screw J^{14} , locating pins J^{15} , stripper pin J^{16} , type face J^{17} , bar J^{18} , stud J^{19} , stop bar J^{20} , post J^{21} , stop screw J^{22} , limiting post J^{23} , removable weights J^{24} ,

radial slots J^{25} , flattened part J^{26} of rod J ; horizontal arm J^{27} , lever J^{28} , lever pivot J^{29} , and the weight J^{30} , the type block J^{12} being also provided with a spring and with recesses corresponding respectively to the 70 spring G^{14} and recesses G^{17} previously described.

After the blade has been printed on the second printing block I it is lifted therefrom and tossed into a suitable receptacle (not shown in the drawings) by the throw-off arm L (Figs. 1, 2, 3, 6 and 7), said arm being pivoted on the pin L^1 and having a bifurcated outer end which embraces the second printing block I , but without contact with it, 75 as plainly shown in Figs. 3 and 6. The throw-off arm is provided with a positioning screw L^2 and is operated in much the same manner as the printing blocks F and I , the lifting off movement being given by 80 the cam L^3 acting through the roller L^4 , lever L^5 , cord L^6 , passing over the idler pulley L^7 and segment pulley L^8 , the latter being integral with the arm. The return movement is effected by the weight L^9 which depends from the segment pulley L^{10} by the cord L^{11} , said pulley, also, being integral with the arm L (Figs. 1, 2, 3, 5, 6 and 7).

The mechanism is automatically stopped by the exhaustion of one or more of the stacks of blades on the stack plate C , in the following manner: The belt which drives the mechanism is guided upon the tight and loose pulleys B^3 and B^9 , respectively, by the shipper arm M , said arm having a 95 forked outer end adapted to embrace the belt and being rigidly secured upon the upper end of the vertical shaft M^1 , the latter being rotatably mounted in the bearings M^2 and M^3 of the bracket M^4 , which is screwed 100 to the edge of the table A^2 (Figs. 1, 3, 4 and 5). The spring M^6 (Fig. 1) acting upon the collar M^6 fixed upon the shaft M^1 and reacting upon the bracket M^4 , tends to throw the shipper arm and, consequently, 105 the belt, to the loose pulley B^9 , but when the mechanism is normally working, this is prevented and the belt guided on the tight pulley B^3 by the latch arm M^7 rigidly mounted on the lower end of the said shaft 110 M^1 , and engaging at its outer end with the latch bar M^8 pivoted at M^9 on the main frame A^1 , and having the shoulder M^{10} engaging with the under edge of the latch arm M^7 (Fig. 18). The engaging end of the 115 latch bar M^8 is normally held up against the latch arm by the spring M^{11} (Fig. 4) and is laterally guided between two pins M^{12} , M^{13} , on the under side of the latch arm. The vertical rod D^8 , upon which the suction 120 carrying arm D is mounted is provided with the horizontal arm M^{14} (Figs. 1, 4 and 5) having at its outer end a vertical adjustable releasing screw M^{15} . When the suction carrying arm D is over a blade stack this re- 125 130

leasing screw M^{14} is directly over the latch bar M^8 which is restraining the belt shipper arm M from throwing the belt onto the loose pulley by the action of the spring M^5 . The screw M^{14} does not, however, descend low enough to engage the latch bar as long as there are blades in the stack on which the suction carrying arm drops, but when the last blade has been removed from this stack, 10 then the suction pad D^{30} drops into the recess in the block C^2 (Figs. 16 and 17) and allows the suction carrying arm and its supporting rod D^3 , and consequently the arm M^{13} and screw M^{14} , to descend far 15 enough for the said screw to engage the latch bar M^8 and by depressing it release the latch arm M^7 and allow the spring M^5 to act and so throw the belt onto the loose pulley B^3 and thereby bring the whole mechanism to rest.

Having now explained the various parts of the machine in detail, I shall proceed to describe its general operation.

The stack place C , having been supplied 25 with blades, the shipper arm M is pulled over to the tight pulley and the latch arm M^7 thus allowed to engage with latch bar M^8 , and the device starts to operate. We will suppose that at starting, the suction 30 carrying arm D , the first printing block F , the first printing arm G , the second printing block I , the second printing arm J , and the throw-off arm L are in the respective positions shown in the diagram Fig. 25, while 35 the suction piston E^1 is in the position shown in Fig. 19 with the inlet port partly uncovered. As the movement progresses, the suction carrying arm D is raised by the lever D^{13} acted on by the cam D^{19} and is 40 then swung by the cam D^{21} over the first printing block F upon which it is dropped by the said cam D^{19} . In the meantime the suction piston has been rising through the action of the cam E^{23} (Fig. 19), but as soon 45 as the carrying arm D has reached the printing block F , the piston is suddenly dropped by its cam E^{23} and the backward flow of air through the connecting pipes insures that the blade is released from the carrying arm 50 and left on the printing block when the former rises again. The parts are now in the position shown in the diagram Fig. 26. The carrying arm D is now lifted again by the cam D^{19} and is swung back over the 55 stack plate C by the action of the weight D^{20} , and in due time is dropped by the said cam D^{19} onto the stack of blades next in order, the stack plate C having in the meantime rotated a quarter turn. In the mean- 60 time the first printing arm G has been lifted from the inking pad H by its cam G^7 and been swung over the printing block F by its cam G^9 and then dropped on the blade which is now lying upon the printing block

F , and printing the blade, the position of 65 the parts being shown in the diagram Fig. 27.

Next, the printing arm G is lifted again by its cam G^7 and then swung back over the inking pad H by the spring G^{10} after which it is dropped upon the inking pad, 70 the latter having just finished making a partial rotation by means of its turning mechanism, as previously herein explained. In the meantime the second printing block I has, by its cam I^4 , been folded over onto the 75 first printing block F , its sharp pointed pins I^{12} , I^{12} , registering in the small depressions in the ends of the pins F^{15} , F^{15} of the first printing block F and the parts are in the relation shown in the diagram Fig. 28. 80 Now the second printing block I returns to its printing position by the action of the weight I^8 , with the first printing block F following it closely, impelled by its cam F^4 and the parts are as shown in the diagram 85 Fig. 29. The dotted lines in Fig. 7 show the two printing blocks F and I swinging over together, and the blade in the act of transit from the block F to the block I . The first printing block F now returns to its 90 printing position by the action of its weight F^{11} , and the second printing arm J is raised from its inking pad K , swung over and dropped on the second printing block I , 95 which carries the inverted blade, by its cam in the same manner as the first printing arm G was operated, and the blade is printed on the other side, the parts being in the position shown in the diagram Fig. 30. Lastly, the second printing arm J returns 100 to its inking position, its inking pad K having in the meantime slightly turned, in a manner exactly similar to that described for the return of the first printing arm G , and the throw-off arm L rises through its 105 cam L^3 , thereby lifting the now wholly printed blade by its ends, tossing the latter into a receptacle (not shown) and the parts stand as in the diagram Fig. 31. The throw-off arm is now returned to its first 110 position by the weight L^9 and the cycle of operations is completed.

It will be obvious that for printing razor blades or other articles on one side only the machine will simply require the omission of certain parts and a slight modification of other parts. I do not limit myself to the specific details of construction.

Having thus described my invention, what I claim as new and desire to secure by Letters Patent is:

1. In a machine for printing on metal, the combination of a rotatable stack-plate for holding supply stacks of metal, a printing block and means for printing on the metal, 125 means for conveying the metal from said stack-plate to said printing-block, and means for automatically turning the stack-plate in

partial rotations whereby the supply stacks of metal are brought successively into position to register with the conveying means.

2. In a machine for printing on metal, the combination of a rotatable stack-plate for holding supply stacks of metal, a printing block and means for printing on the metal, means for conveying the metal from said stack-plate to said printing block, a spindle 10 on which said stack-plate is mounted, a friction disk rigidly secured to said spindle, a pulley loosely mounted on said spindle and on which said friction disk is made to bear and support said spindle, and means for interrupting the rotary movements of said spindle at stated intervals.

3. In a machine for printing on metal, the combination of a rotatable stack-plate for holding supply stacks of metal, a printing block and means for printing on the metal, means for conveying the metal from said stack-plate to said printing block, means for rotating said stack-plate, latch pieces on said stack-plate, a latch for engaging said latch pieces, and means for causing the operation of the latch for stopping the rotation of the stack-plate at stated intervals.

4. In a machine for printing on metal, the combination of a rotatable stack-plate for holding supply stacks of metal, a printing block and means for printing on the metal, means for conveying the metal from said stack-plate to said printing block, a spindle on which said stack-plate is mounted, a pulley loosely mounted on said spindle, a friction disk rigidly secured to said spindle and adapted to support the same and to give rotary motion thereto by bearing on said pulley, latch pieces on said stack-plate, a pivotal 40 latch adapted to engage said latch pieces, and a pull rod and actuating connections therewith for disengaging said latch from said latch pieces at stated intervals.

5. In a machine for printing on metal, the combination of a stack-plate for holding supply stacks of metal, a printing block and means for printing on the metal, a carrying-arm mounted to move vertically and swing laterally, a suction cylinder, said carrying-arm being provided at its outer end with a suction pad having an annular recess surrounding a solid central portion and forming a suction space, and with communicating passage ways leading from said annular suction space through said carrying-arm, and by suitable means connecting with said suction cylinder, and means for causing said carrying-arm to move with adhering metal from said stack-plate to said printing block and back to the stack-plate.

6. In a machine for printing on metal, the combination of a stack-plate for holding supply stacks of metal, a printing block and means for printing on the metal, a carrying-arm for delivering metal from said stack-

plate to said printing block, the said carrying-arm being provided with a lateral extension piece, fixed standards for contacting with said lateral extension piece, a rod to which said carrying-arm is secured, a lever having connections for supporting said rod, means for actuating said lever thereby imparting a vertical reciprocating motion to said rod and carrying-arm, and means for giving said rod and carrying-arm a back and forth turning movement within the limits permitted by said extension piece and said standards.

7. In a machine for printing on metal, the combination of a stack-plate for holding supply stacks of metal, a printing block and means for printing on the metal, a carrying-arm adapted to take metal from said stack-plate and deliver the same to said printing block, said carrying-arm being connected with a rod, a lever having connections for supporting said rod and imparting vertical movements thereto, means for partially rotating the said rod and carrying-arm in one direction comprising a cam, a roller, a lever, a pull-rod and an arm, and means for partially rotating said rod and carrying-arm in the reverse direction comprising a weight, an arm, a cord, and an idler pulley, and means for limiting the turning movements of said carrying-arm in each direction.

8. In a machine for printing on metal, the combination of a stack-plate for holding supply stacks of metal, a printing block, a pivotal arm on which said printing block is supported, segment pulleys on said arm, connections with said segment pulleys for rotating the said arm on its pivot, thereby turning the printing block upside down and right side up, means for printing the metal when on said printing block, and means for conveying the metal to be printed from said stack plate to said printing block.

9. In a machine for printing on metal, the combination of a pivotal printing block, means for printing on the metal, means for placing the metal to be printed on the printing block, and means for turning the printing block upside down and right-side up whereby the metal may be turned over and detached from said printing block.

10. In a machine for printing on metal, the combination of a pivotal printing block, means for printing on the metal, a carrying-arm adapted to take the metal from a source of supply and transfer the same to said printing block, means for operating said carrying-arm, and means for turning the printing block upside down and right-side up whereby the metal may be turned over and detached from said printing block.

11. In a machine for printing on metal, the combination of a pivotal printing block, means for printing on the metal, a carrying-arm adapted to take the metal from a source

- of supply and transfer the same to said printing block, means for operating said carrying-arm, means for turning said printing block up-side down and right-side up whereby the metal may be turned over and detached from said printing block, a second printing block for receiving the metal when reversed by the first printing block, and means for printing on the metal when 5 the same is on the second printing block.
12. In a machine for printing on metal, the combination of a printing block, means for placing and positioning the metal to be printed on the said printing block, a type block, a printing arm to which said type block is secured, an inking pad, and means for causing the printing arm to move from said printing block to said inking pad and after taking ink return to said printing block.
13. In a machine for printing on metal, the combination of a printing block, means for placing the metal to be printed on said printing block, a printing arm, a type block secured to said printing arm, an inking pad, means for causing said printing arm to move vertically and also turn back and forth between said printing block and said inking pad and descend upon each of them, and means for detaching the type-face from the metal printed upon when said printing arm starts to rise therefrom after printing.
14. In a machine for printing on metal, the combination of a printing block, means 35 for placing the metal to be printed on the said printing block, an inking pad, a printing arm, a type block secured to said printing arm, a rod to which said printing arm is secured, an arm and cam adapted to cause said rod and printing arm to move vertically, an arm and cam adapted to impart partial rotation to said rod and printing arm in one direction, a spring having one end secured to a fixed part, and an arm 40 connection with said rod at its other end, whereby partial rotation in the opposite direction may be given to said rod and printing arm.
15. In a machine for printing on metal, the combination of a printing block, means 50 for placing the metal to be printed upon said block, an inking pad, a type block, a printing arm to which said type block is secured, means for causing said printing 55 arm to move back and forth from said printing block to said inking pad, means for limiting said back and forth movements, and means for locating the metal to be printed and the type for printing with relation to each other.
16. In a machine for printing on metal, the combination of a printing block, an inking pad, a type block, a printing arm to which said type block is secured, means 60 for causing said printing arm to move back and forth from said printing block to said inking pad for taking ink and for printing, and means for diminishing the force which operates the printing arm prior to the application of the type to the inking pad.
17. In a machine for printing on metal, the combination of a stack plate for holding supply stacks of metal, a printing block, a carrying-arm adapted to transfer the metal from said stack-plate to said printing block, an inking pad, a printing arm, and means for causing said printing arm to move back and forth between said inking pad and the metal transferred by said carrying-arm to said printing block.
18. In a machine for printing on metal, the combination of a rotatable stack-plate for holding supply stacks of metal, means for giving partial rotations to said stack-plate, a printing block, a carrying-arm for 75 transferring the metal from said stack-plate to said printing block, means for giving vertical and partial rotating movements to said carrying-arm back and forth between said printing block and the metal on 80 said stack plate, said movements being in harmony with the partial rotations of said stack plate, an inking pad, a printing arm, and means for giving vertical and partial 85 rotating movements to said printing arm back and forth between said printing block and said inking pad, said movements being in harmony with the movements of the carrying-arm for delivering the metal to be 90 printed on said printing block.
19. In a machine for printing on metal, the combination of a stack-plate for holding supply stacks of metal, a pivotal printing block, a carrying-arm adapted to transfer the metal from said stack plate to said 95 printing block, an inking pad, a printing arm for carrying type for printing, means for causing said printing arm to move the type carried thereby back and forth between said inking pad and the metal transferred to said printing block by said carrying-arm, and means for turning said printing block up-side down and right-side up 100 after metal transferred thereto by said carrying-arm has been printed.
20. In a machine for printing on metal, the combination of a printing block, a printing arm carrying type for printing, an inking pad, a movable support on which the same is carried, means for causing the printing arm to move the type back and forth between the inking pad and the printing block, means for oscillating the support for the inking pad synchronously with the movements of the printing arm, and means 110 for locking said inking pad against backward movement during the backward oscillation of its support.
21. In a machine for printing on metal, the combination of a printing block, a print-

- ing arm carrying type for printing, an oscillating support and an inking pad frictionally supported thereon, means for causing said printing arm to move back and forth between the inking pad and the printing block, connections between said printing arm and support for oscillating the latter, and means for preventing backward movement of the inking pad upon the backward oscillation of its support. 22. In a machine for printing on metal, the combination of a rotatable stack plate for holding supply stacks of metal, means for imparting partial rotations to said stack plate, a printing block, means for conveying the metal from said stack plate to said printing block, a printing arm for carrying type for printing the metal on said printing block, an inking pad, and means for causing the type carried by said printing arm to take ink from different parts of said inking pad. 23. In a machine for printing on metal, the combination of a pivotal printing block, means for conveying the metal from a source of supply to said printing block, means for printing on one side of the metal, means for turning said printing block upside down and right-side up, a second printing block adapted to receive the metal from the first printing block with the printed face down, and means for printing on the exposed side of the metal when on said second printing block. 24. In a machine for printing on metal, the combination of a pivotal printing block, means for conveying the metal from a source of supply to said printing block, means for printing on one side of the metal, a second pivotal printing block, means for turning both said printing blocks up-side down and right-side up, said second printing block being caused to fold on the first printing block after the metal has been printed on one side, and means for transferring the metal from the first to the second printing block after the second has been folded on the first. 25. In a machine for printing on metal, the combination of a pair of printing blocks adapted to turn on a common pivot, means for transferring metal from a source of supply to the first printing block, means for positioning the metal on said printing block, means for printing on one side of the metal, means for causing the second printing block to fold on the metal after being printed on one side while on the first printing block, means for positioning the metal on the second printing block when folded onto the first, and means for turning both of said blocks on their pivot, and means for printing on the reverse side of the metal when transferred to said second printing block. 26. In a machine for printing on metal, the combination of a pair of printing blocks, means for placing metal to be printed on one of said blocks, a printing arm, an inking pad, means for causing said printing arm to move back and forth between said printing block and said inking pad, a second printing arm for printing the reverse side of the metal, a second inking pad, means for causing said second printing arm to move back and forth between the second printing block and the second inking pad, and means for reversing and transferring the metal from the first to the second printing block. 27. In a machine for printing on metal, the combination of a printing block, means for placing metal on said printing block, an inking pad, a printing arm, means for causing said printing arm to move back and forth between said inking pad and said printing block and to print on the metal when on said printing block, and means for throwing the printed metal off said block after being printed. 28. In a machine for printing on metal, the combination of a stack plate for holding supply stacks of metal, a printing block, a carrying arm for transferring metal from said stack plate to said printing block, an inking pad, a printing arm, means for causing said printing arm to move back and forth between said inking pad and said printing block, and means for throwing the metal off said printing block after being printed by said printing arms. 29. In a machine for printing on metal, the combination of a printing block, means for placing metal to be printed on said printing block, an inking pad, a printing arm, a type block secured to said printing arm, means for causing said printing arm to move the type back and forth between said inking pad and said printing block, means for causing said inking pad to rotate in one direction, means for detaching the metal from the type after printing and means for removal of the metal from the printing block after printing. 30. In a machine for printing on metal, the combination of a rotatable stack plate for holding supply stacks of metal, a printing block, a carrying arm for placing the metal on said printing block, means for imparting partial rotations to said stack-plate, means for imparting vertical and turning movements to said carrying arm to and from the stack and said printing block, an inking pad, a printing arm, means for causing said printing arm to move back and forth between said inking pad and said printing block, and means for the removal of the metal from said printing block after printing. 31. In a printing machine, the combina-

tion with a pair of supports and means for printing upon an article while resting thereon, of means for inverting one of the supports between successive printing operations 5 and thereby turning the article upside down and transferring it to the other support.

32. In a printing machine, the combination of a pair of printing blocks, each adapted to support an article to be printed, means 10 for closing one block upon the other and for separating the same, means for inverting said blocks while in their closed position, and printing devices coöperating with each block to print upon the article while supported thereon.

33. In a printing machine, the combination of a pair of plates each adapted to receive and support an article to be printed upon, means for independently swinging said plates in a semicircle about a common axis, and printing devices coöperating with each plate to print upon an article supported thereon.

34. In a printing machine, the combination 25 with means for printing upon the opposite sides of an article successively, of a printing block adapted to support said article during the second printing operation and provided with recesses arranged to 30 overlie the matter printed on said article by the first printing operation.

35. In a printing machine, the combination 35 of a pair of printing blocks adapted to be folded together and to be separated, said blocks being each provided with positioning devices arranged to register when the blocks are folded together, means for inverting said blocks while folded together, and means for printing upon an article supported by said blocks.

36. In a printing machine, the combination of a support for the article to be printed and means for positioning said article on the support, an oscillating printing arm

carrying the type for printing, an inking 45 pad, an adjustable stop limiting the oscillating movement of the printing arm to its printing position, means constantly tending to hold said arm against its stop, and means for positively swinging said arm away from 50 said stop.

37. In a printing machine, the combination of a printing block, an inking pad, an oscillating printing arm provided with type and means for operating the same, a stripping device adapted to engage the article and detach it from the type face, and means for preventing said stripping device from coming in contact with the inking pad.

38. In a printing machine, the combination of a movable printing block and means for moving the same into and out of printing position, upwardly-projecting positioning pins carried by said block and arranged to enter openings in the article to be printed, a type block having recesses in its type face to receive said positioning pins, and means for moving the type block into and out of printing position.

39. In a printing machine, the combination of a pair of printing blocks each adapted to support an article to be printed, means for closing one block upon the other and for separating the same, positioning pins carried by each block and adapted to 75 register with those on the other block when said blocks are in closed position, a type block for each printing block, each type block being provided with recesses in its type face to receive the positioning pins 80 on the corresponding printing block, and means for moving said type blocks into and out of printing position.
